UNITED STATES PATENT OFFICE

LE ROY A. DROESCHER, OF WILLOW GROVE, PENNSYLVANIA, ASSIGNOR TO C. H. WHEELER MANUFACTURING COMPANY, OF PHILADELPHIA, PENNSYLVANIA, A CORPORATION OF PENNSYLVANIA

REFRIGERATING SYSTEM

Application filed March 10, 1931. Serial No. 521,414.

My invention relates to refrigerating systems of the character in which the refrigerating medium, as brine or equivalent, is circulated through a tank in which are disposed 5 the containers for the material to be cooled or frozen.

My invention resides in a refrigerating system of the character hereinafter described and claimed.

10 For an understanding of my invention reference is to be had to the accompanying drawing, illustrative of one of the forms my invention may take.

In the drawing, which is an elevational 15 view, partly in section, T represents a tank which may be constructed of concrete or the like in which is embedded the structure 1 of any suitable material for reinforcement, proofing against leakage, or similar purposes.

20 The structure 1 may in itself constitute a metal tank covered inside and outside with concrete or equivalent.

From a tank or reservoir R containing the 25 refrigerating medium, as brine or equivalent, of suitably low temperature for the purposes involved, including the manufacture of artificial ice, that medium is withdrawn by the pump P and supplied to the header or manifold 2.

30 Within the tank T is disposed any suitable number of refrigerating receptacles or cans C, each of which, in the example illustrated, is provided with a surrounding casing K, spaced therefrom, terminating short of the 35 top of the can C, and extending below the bottom of the can to form a wall of a compartment 3 with which communicates a connection 4 from the manifold 2. In the example illustrated the lower end of the casing K extends into a groove in a sealing member 5, of wood or the like, resting upon or embedded 40 in the bottom of the tank T.

Between the can C and its casing K may be disposed ribs or strips 6 serving both as 45 heat transfer fins and as means for defining vertical individual passages for cooling medium connecting with the compartment 3. Structure of this character is shown in my application Serial No. 518,679, filed February 27, 1931.

In the arrangement shown there is delivered to each can an individual supply of cooling medium which flows upwardly through the casing K, overflowing its top into the tank T from which the cooling medium from all the individual casings K is withdrawn through the connection 7. 55

Within the tank T may be provided the wall or weir 8 extending to height short of the tops of the cans C or approximately to 60 the tops of the casings K. The cooling medium overflowing the tops of the casings K accumulates to the left of the weir 8, overflowing the weir into the compartment 9 with which the aforesaid connection 7 communicates. 65

The medium is drawn through the pipe 7 into the chamber 10 of a flash evaporator F which, in the example illustrated, comprises the shell 11 into which the cooling medium 70 is delivered through spray nozzles 12, the liquid continuing downwardly through the shell 11, to one side of the baffle 13, over strips or gratings 14 for retarding its fall and breaking it up or further subdividing it. 75

In the evaporator F is maintained an extremely high vacuum, or low absolute pressure, as of the order of two millimeters of mercury, in the case where brine is the cooling medium for freezing water into ice in 80 the cans C. From one side of the baffle 13 vapor passes through the connection 15 into the suction chamber of the ejector E having the nozzle structure N utilized in expanding steam or other elastic motive fluid, 85 under suitable pressure, into jets which entrain the vapor aforesaid, the mixture passing through the diffuser structure G and is delivered at higher pressure through the connection 16 into the lower portion of the 90 barometric condenser 17.

The temperature of the brine or cooling medium is lowered to the desired or suitable degree in the flash evaporator F from whose shell 11 it passes through the barometric column 18 into the aforesaid receptacle or reservoir R from which it is withdrawn by the pump P and returned to the receptacles in the tank T. 95

The rate of withdrawal of vapor from the 100

evaporator F is sufficient to reduce the temperature of the cooling medium to the desired degree. The vacuum within the evaporator F is greater than that corresponding to the temperature of the entering injection or cooling water in the condenser 17, which though shown as a barometric condenser, may be of any other suitable type, as a surface condenser.

10 To make up for the vapor withdrawn from the evaporator F by the ejector E, there is provided in the pipe 19, delivering make-up water, a valve 20 controlled by the float 21 resting upon the cooling medium within the reservoir R. As the level of the medium falls valve 20 is opened to admit sufficient water from the line 19 to the connection 22, which delivers into the chamber 10 of the evaporator F, to maintain substantially constant the total cooling medium of the system. The make-up water becomes intermingled with the cooling medium delivered by the connection 7, and in mixture therewith is chilled to suitably low temperature in the evaporator.

25 To the water box or chamber 23 of the condenser 17 is delivered its cooling medium, such as cooling water, through the pipe 24 controlled by the valve 25. Cooling water is delivered through the spray nozzles 12 and descends over the gratings 14. The finely divided cooling water comes into contact with the vapor and non-condensables delivered by the ejector E through the connection 16, condensing the condensable components which as liquid passes through the column 26, into any suitable receptacle 27, having a port or aperture 28 through which the water passes to waste, or, if desired, is delivered to a cooling tower or other suitable cooling means, and then re-used as cooling water delivered through the pipe 24.

40 The non-condensable vapors and gases, as leakage air, are drawn off from the top of the condenser 17 through the passage 29 to the suction chamber of the steam operated ejector E1 discharging into the jet inter-condenser 30 from which non-condensables are withdrawn and raised in pressure by the 45 third ejector E2 which discharges to atmosphere or any other suitable region. The inter-condenser 30 is in the example illustrated a barometric condenser whose cooling water is derived from the pipe 24 delivered through 50 spray nozzles 12. The suction chamber of the ejector E2 communicates with the interior of the condenser 30 through the downwardly directed pipe 31, generally similar to the connection 16. The water from the condenser 30 is discharged through the column 32 into the column 26, or separately into the receptacle 27, or to suitable separate receptacle.

What I claim is:

65 1. A system for producing ice comprising

a tank, a plurality of receptacles therein for holding water to be frozen, an evaporator, a connection from said tank conveying cooling medium therefrom to said evaporator in which it is lowered in temperature, means 70 for maintaining high vacuum in said evaporator, a receptacle for cooling medium from said evaporator, a connection communicating with said evaporator through which make-up water is delivered to be co-mingled 75 with the cooling medium and lowered in temperature therewith, means controlling delivery of make-up water through said connection in response to variations in the amount of cooling medium from said evaporator, and means for delivering the cooling medium to said tank.

2. A system for producing ice, comprising a tank having a plurality of receptacles therein for holding water to be frozen, a reservoir for a cooling medium, a connection from said reservoir conveying the cooling medium therefrom to said tank, a flash evaporator, a connection from said tank conveying the cooling medium therefrom to said evaporator, an ejector for withdrawing vapors from said evaporators, and raising them in pressure, a condenser into which said ejector discharges, means for delivering cooling water to said condenser, means for maintaining a vacuum in said condenser, said ejector maintaining in said evaporator a vacuum higher than that corresponding with the temperature of said cooling water in said condenser, means for delivering make-up liquid to said evaporator, means for causing said make-up liquid to co-mingle with the cooling medium within the evaporator, and means for returning the cooling medium concentrate including said make-up liquid to 105 said reservoir.

3. A system for producing ice, comprising a tank having a plurality of receptacles therein for holding water to be frozen, a reservoir for a cooling medium, a connection from said reservoir conveying the cooling medium therefrom to said tank, a flash evaporator, a connection from said tank conveying the cooling medium therefrom to said evaporator, said evaporator comprising a chamber in which said cooling medium is sprayed, a reservoir, a barometric column delivering the cooling medium concentrate from said evaporator to said reservoir, an ejector for withdrawing vapors from said evaporator to maintain high vacuum therein, a condenser into which said ejector discharges, and means for maintaining a vacuum in said condenser.

4. A system for producing ice, comprising a tank having a plurality of receptacles therein for holding water to be frozen, a reservoir for a cooling medium, a connection from said reservoir conveying the cooling medium therefrom to said tank, a flash

evaporator, a connection from said tank conveying the cooling medium therefrom to said evaporator, said evaporator comprising a chamber in which said cooling medium is sprayed, a barometric column delivering the cooling medium from said evaporator to said reservoir, an ejector for withdrawing vapors from said evaporator to maintain high vacuum therein, a barometric condenser into which said condenser discharges, an ejector producing a vacuum in said barometric condenser, a condenser into which said last named ejector discharges, and an ejector for producing a vacuum in said last named condenser.

5 5. A system for producing ice, comprising a tank having a plurality of receptacles therein for holding water to be frozen, a reservoir for a cooling medium, a connection from said reservoir conveying the cooling medium therefrom to said tank, a flash evaporator, a connection from said tank conveying the cooling medium therefrom to said evaporator, an ejector for withdrawing vapors from said evaporator, and raising them in pressure, a condenser into which said ejector discharges, means for delivering cooling water to said condenser, means for maintaining a vacuum in said condenser, said 20 ejector maintaining in said evaporator a vacuum higher than that corresponding with the temperature of said cooling water in said condenser, means for delivering make-up water to said evaporator, means in said evaporator for spraying said make-up water to co-mingle with the condensate of said cooling medium, and means for delivering the condensate and the make-up water to said reservoir.

25 6. A system for producing ice, comprising a tank having a plurality of receptacles therein for holding water to be frozen, a reservoir for a cooling medium, a connection from said reservoir conveying the cooling medium therefrom to said tank, a flash evaporator, a connection from said tank conveying the cooling medium therefrom to said evaporator, said evaporator comprising a chamber in which said cooling medium is sprayed, an ejector for withdrawing vapors from said evaporator to maintain high vacuum therein, a condenser into which said ejector discharges, means for maintaining a vacuum in said condenser, means for delivering make-up water to said flash evaporator, means in said evaporator for spraying said make-up water to co-mingle with the condensate of said cooling medium, and means for delivering the condensate and make-up water to said reservoir.

30 7. A system for producing ice, comprising a tank having a plurality of receptacles therein for holding water to be frozen, a reservoir for a cooling medium, a connection from said reservoir conveying the cooling medium

therefrom to said tank, a flash evaporator, a connection from said tank conveying the cooling medium therefrom to said evaporator, said evaporator comprising a chamber in which said cooling medium is sprayed, an ejector for withdrawing vapors from said evaporator to maintain high vacuum therein, a barometric condenser into which said ejector discharges, an ejector producing a vacuum in said barometric condenser, a condenser into which said last named ejector discharges, an ejector for producing a vacuum in said last named condenser, means for delivering make-up water to said evaporator, means in said evaporator for spraying said make-up water to co-mingle with the condensate of the cooling medium, and means including a barometric column for delivering the condensate and make-up water to said reservoir.
